United States Patent Office.

JOHN McFADDEN, OF CADIZ, OHIO.

Letters Patent No. 77,999, dated May 19, 1868.

IMPROVED TRUSS-SUPPORTER.

The Schedule referred to in these Letters Patent and making part of the same.

TO ALL WHOM IT MAY CONCERN:

Be it known that I, JOHN McFADDEN, of Cadiz, in the county of Harrison, in the State of Ohio, have invented a new and improved Truss-Supporter; and I do hereby declare the following to be a full, clear, and exact description thereof, which will enable those skilled in the art to make and use the same, reference being had to the accompanying drawing, forming part of this specification, in which drawing—

Figure 1 represents a front elevation of this invention.

Figure 2 is a rear elevation thereof.

Similar letters indicate corresponding parts.

This invention consists in a truss-pad provided with a series of radiating buckles, which are intended to receive and retain a waist-strap, two thigh-straps, and a shoulder-brace, in such a manner that, by adjusting the several straps in their buckles, the pad can be brought to bear on the afflicted part with more or less force, and all injurious or painful strain can be avoided.

A represents a truss-pad, which, by preference, is provided with one or more internal springs, so that it acts on the afflicted part of the human body with a yielding pressure.

This pad is provided with a series of radiating buckles, *a b c d e*, as clearly shown in fig. 1 of the drawing. The buckles *a* and *e* serve to fasten the waist-strap *B*, and to this strap is secured one of the thigh-straps, *C*, which, when the truss-pad is in position, extends down on the back of the body, and through between the legs, and is secured in the buckle *e*. The second thigh-strap, *D*, extends from the buckle *c* around the upper part of the thigh to the buckle *d*, and this strap is steadied in its position by the additional brace *D'*, which extends from the back part of the waist-strap and connects with said thigh-strap *D*, as shown in fig. 2. From the buckle *b* extends the shoulder-brace *E*, which passes over one of the shoulders and down on the back, connecting by a buckle, *f*, with waist-strap *B*.

By adjusting the several straps in their buckles, the truss-pad can be brought to bear on the afflicted part with any desired force, and it can be made to act from above, or from below, or from either side, as the nature of the rupture may require, and, if the straps are properly adjusted, the pad is firmly retained in position, so that the same is not liable to become displaced by the motions of the body. By releasing one or more of the straps, the body can be temporarily relieved from the pressure without removing the truss entirely.

By this arrangement, a truss is obtained which acts on the rupture with a positive pressure, and which can be readily adjusted to conform in its action to the nature of the rupture.

Having thus described my invention, what I claim as new, and desire to secure by Letters Patent, is—

A truss-pad, *A*, provided with a series of radiating buckles, *a b c d e*, and acting in combination with the straps *B C D E*, substantially as and for the purpose described.

Also the additional brace *D'*, in combination with the pad *A*, waist-strap *B*, and thigh-strap *D*, substantially as and for the purpose set forth.
